CLAIM

The ornamental design for a articulated splint, as shown and described.

DESCRIPTION

FIG. 1 is a perspective view of an articulated splint, showing our new design, in unfolded configuration;

FIG. 2 is a first side view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a second side view thereof;

FIG. 8 is a perspective view of the splint in a completely folded configuration; and,

FIG. 9 is a side view of the splint in the folded configuration thereof.
